TOBACCO CAN

George V. Wilson and Samuel P. Darkins,
Homestead, Pa.

Application July 23, 1945, Serial No. 606,642

1

This invention relates to a can generally of the type commonly used as a container for receiving and marketing a small quantity of smoking tobacco, and important objects and advantages of the invention are to provide a tobacco can of the character described, which embodies conveniently operable means for successively elevating the tobacco within the can in order to allow the contents to be easily removed from the upper end of the container as the tobacco is used up, which includes a sectionally separable wrapper for the tobacco so that the emptied portions of said wrapper may be readily removed to thereby further facilitate the removal of the tobacco as required, which is simple in its construction and arrangement, durable and efficient in its use, compact, attractive in appearance, and comparatively economical in its manufacture.

With the foregoing and other objects in view which will appear as the description proceeds, the invention consists of the novel construction, combination and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a front elevational view, partly in cross section, of a tobacco can constructed in accordance with the invention. Figure 2 is a bottom plan view thereof. Figure 3 is a top plan view of the shiftable bottom embodied in the present invention. Figure 4 is a front elevational view of a tobacco can embodying a modified form of shiftable bottom. Figure 5 is a fragmentary side elevational view of the modified form of tobacco can, and Figure 6 is a top plan view of the modified shiftable bottom.

Referring in detail to the drawing 1 represents a container for tobacco generally of the conventional construction and contour now in common use for marketing a small quantity of smoking tobacco. The container may be constructed of sheet metal or of any other suitable material, and is provided with a hinged lid 2, at its top, in the usual manner.

The container 1 comprises the comparatively wide, flat, front and back walls 3 and 4, and the relatively narrow, rounded side walls, respectively indicated at 5 and 6. The lower edge margins of all of said walls are turned inwardly to form an interiorly disposed roll flange 7 which provides

2

and surrounds a large opening 8 at the lower end of the container.

A shiftable bottom 9, preferably constructed of resilient sheet metal, is mounted in the container 1, and is vertically adjustable in the latter. Due to the roll flange 7, the bottom 9 cannot be removed from the container through the opening 8 at the lower end of said container.

The bottom 9 is normally slightly arcuated, with its convex curvature being disposed upwardly. The peripheral contour of the bottom conforms generally to the transverse cross sectional shape of the interior of the container 1. Each end of the bottom is provided with an upwardly projecting retaining flange, respectively indicated at 10 and 11. The retaining flanges are concavo-convex in transverse cross section to conform to the inner surface contours of the rounded side walls 5 and 6, against which latter said retaining flanges are frictionally engaged.

It will here be noted that, when the bottom 9 is straightened by pressure upon its convex top surface, the retaining flanges 10 and 11 extend vertically at right angles with respect to said straightened bottom, and the entire outer surface areas of said retaining flanges are frictionally engaged by the adjacent inner surfaces of respective side walls 5 and 6.

As the resiliency of the bottom 9 tends to maintain the arcuate disposition of the bottom, it will be obvious that, normally only the top edges of the retaining flanges 10 and 11 will be in engagement with respective side walls 5 and 6, while the latter are slightly spaced from the lower ends 35 of said flanges, as clearly illustrated in Figure 1. Such edge engagement of the flanges will facilitate the elevating adjustment of the bottom 9, but the spreading action of the resiliently tensed bottom 9 will retain the latter in the adjusted 40 position in the container 1. The height of the retaining flanges and the engagement of the latter with the side walls 5 and 6 prevents the displacement of the bottom 9 from its horizontal position in the container.

45 The tobacco 12, sold in the container 1, is enclosed, for preservative purposes, in a tough, waxed paper wrapper 13 in the usual manner. As the tobacco is used up, the periodic adjustment, to elevate the tobacco, will project the emptied portion of the wrapper above the top 50 of the container. To facilitate the detachment of such emptied projecting portions of the wrapper, the latter is suitably scored to provide a plurality of regularly spaced tear lines 14, which 55 extend horizontally around the wrapper.

In practice, the elevating adjustment of the bottom 9 in the container 1 is effected by simply inserting one or several fingers through the opening 8 at the lower end of the container, and pushing upwardly against said bottom to force the latter, together with the wrapped tobacco, to the desired elevated position.

While tobacco is being removed from the container 1 the operation necessarily involves some downward pressure upon the wrapped tobacco usually caused by releasing the top of the packed tobacco by finger digging action, so that the latter may be poured from the container into a pipe or upon a cigarette paper.

As the lower end of the wrapped tobacco is seated normally upon the center of the upwardly convexed bottom 9, as shown in Figure 1, the downward pressure, caused by the tobacco removal operation, will be imparted to said bottom and tend to straighten the latter. This straightening action expands the bottom longitudinally and causes the full areas of the retaining flanges 10 and 11 to engage respective side walls 5 and 6 under the increased spreading tension of the depressed bottom, thereby securing the latter against downward movement in the container during the tobacco removal operations.

The modified form of container 15, disclosed in Figures 4, 5, and 6, has each of its rounded side walls 16 formed with a vertically aligned row of horizontally extending corrugations 17. The normally upwardly bowed shiftable bottom 18 has each of its ends formed with an extension or retaining lug 19 which engages in opposed corrugations 17 in respective side walls 16. Owing to

the curvature of the bottom 18, the latter may be shifted upwardly in the container 16, but cannot be forced in the downward direction. In practice, the operation of the modified form of the device is identical to that described relatively to the preferred form.

The present invention provides a most efficient device of its kind, which may be economically manufactured, and successfully employed for the purpose and in the manner herein set forth.

What we claim is:

The combination with a tobacco can including a pair of side walls, of a shiftable resilient bottom mounted in the can, said bottom being bowed longitudinally with the convex curvature thereof being disposed upwardly, an upwardly disposed retaining flange carried at each end of said bottom, the free top edge portion of each of said flanges frictionally engaging the inner surface of respective side walls, and the lower attached end of each of said flanges being spaced from the inner surface of respective side walls.

GEORGE V. WILSON.
